CLAIM

The ornamental design for a controller device, as shown and described.

DESCRIPTION

FIG. 1 is an isometric view of a controller device in accordance with a first variant of the present disclosure; FIG. 2 is a front view of the controller device of FIG. 1; FIG. 3 is a rear view of the controller device of FIG. 1; FIG. 4 is a first side view of the controller device of FIG. 1; FIG. 5 is a second side view of the controller device of FIG. 1;

FIG. 6 is a top view of the controller device of FIG. 1; FIG. 7 is a bottom view of the controller device of FIG. 1; FIG. 8 is an isometric view of a controller device in accordance with a second variant of the present disclosure; FIG. 9 is a front view of the controller device of FIG. 8; FIG. 10 is a rear view of the controller device of FIG. 8; FIG. 11 is a first side view of the controller device of FIG. 8;

FIG. 12 is a second side view of the controller device of FIG. 8;

FIG. 13 is a top view of the controller device of FIG. 8; and, FIG. 14 is a bottom view of the controller device of FIG. 8. The broken lines in the drawings depict portions of the controller device which form no part of the claimed design.

1 Claim, 10 Drawing Sheets
